UNITED STATES PATENT OFFICE

2,065,945

MINING MACHINE

Nils D. Levin, Columbus, Ohio, assignor to The Jeffrey Manufacturing Company, a corporation of Ohio

Application January 29, 1934, Serial No. 708,814

31 Claims. (Cl. 262—28)

The present invention relates to mining machines of the type adapted to the mining of coal, although it should be understood that it may have a general application.

5 One of the objects of the invention is to provide a mining machine equipped with an elongated cutter bar which is mounted in a head adapted to quickly revolve so as to position the cutter bar in different planes.

10 A further object of the invention is to provide improved and efficient power transmitting mechanism for effecting a turnover of the cutter head.

More particularly, the object of the invention is to provide in a mining machine turn-over head mechanism for a kerf-cutter in combination with mechanism for adjusting the elevation of the kerf-cutter in order to increase the range of cutting between the floor and roof of the mine entry or room and so that horizontal kerf-cutting may be effected at the floor and at the roof and intermediate the floor and roof in mine veins of various heights.

15 The invention is exemplified in the combination and arrangement of parts shown in the accompanying drawings, and described in the following specification, and it is more particularly pointed out in the appended claims.

20 In the accompanying drawings, Fig. 1 is a plan view of a track mounted mining machine embodying the present invention;

Fig. 2 is an elevational view of the track mounted mining machine shown in Fig. 1;

Fig. 3 is a sectional elevation taken along the plane of the line 3—3 of Fig. 1;

25 Fig. 4 is a fragmentary sectional view showing details of locking mechanism for securing the cutter head in desired position, the view being taken on the line 4—4 of Fig. 5, looking in the direction of the arrows;

30 Fig. 5 is a fragmentary plan view of the turnover head and its mounting, parts being broken away to show certain details of the drive mechanism;

Fig. 6 is a sectional view taken on the line 6—6 of Fig. 5, looking in the direction of the arrows;

Fig. 7 is a sectional view taken on the line 7—7 of Fig. 5, looking in the direction of the arrows;

35 Fig. 8 is an enlarged sectional elevation of a portion of the machine shown in Fig. 1, and taken on the line 8—8 thereof;

Fig. 9 is an enlarged sectional elevation on the line 9—9 of Fig. 10;

40 Fig. 10 is a diagrammatic plan view showing

the relative positions of the parts of the turntable shown in Fig. 1;

Fig. 11 is an enlarged sectional elevation of the connections to the machine for swinging the turntable at a feeding speed;

Fig. 12 is an enlarged sectional elevation of the pawl and ratchet mechanism for effecting reversal of the swinging feeding movement of the turntable and kerf-cutting mechanism;

Fig. 13 is an elevational view showing brake mechanism associated with the shaft and the worm which constitutes part of the swinging feeding mechanism for the kerf-cutter;

Fig. 14 is a sectional elevation showing part of the structure illustrated in Fig. 12; and

Fig. 15 is a sectional elevation taken on the line 15—15 of Fig. 12.

45 Referring more particularly to the drawings, and especially to Figs. 1 and 2, it will be seen that the supporting frame 16 is mounted on wheels 16a, 16a, which are adapted to travel on the mine track 16b. Mounted on the frame 16 is a supporting ring 17 around which is distributed a series of supporting rollers 18, 18. The ring 17 is mounted for adjustment on three upright standards 19, 19 at the front end of the frame 16 and on the rear central standard 19a at the central portion of the frame 16, as shown in Fig. 1. The ring 17 may be adjusted in elevation and inclination by means of such structure as that shown in the Levin Re-issue Patent No. 17,603, granted Feb. 25, 1930, for an Improvement in mining machines. The adjustments in elevation and inclination may be effected by power-operated mechanism controlled by clutches individual to each standard as illustrated in Levin Patent No. 1,353,054, granted September 14, 1920, for an Improvement in mining machines, or the adjustments referred to herein may be made in accordance with Levin Patent No. 1,904,489, granted April 18, 1933. It should be understood that after the ring 17 has been adjusted in elevation and inclination it remains in fixed relation to the supporting frame 16 during the operation of the kerf-cutting mechanism.

50 Mounted on the ring 17 so as to partake of the adjustments thereof in elevation and inclination, is a turntable 20. As shown in Fig. 3, a peripheral flange 21 supports the turntable 20 on the rollers 18. By means of an electric motor 22 connected to mechanism as illustrated in Figs. 8 to 15 inclusive, the turntable 20 may be rotated relatively to the supporting ring 17 and about the center thereof.

On the rear portion of the frame 16 are mounted an additional motor 23 and power transmission mechanism 24 for effecting transportation of the machine along the mine track 16b from place to place in the mine. The power transmission mechanism 24 is also connected to a cable reel 25 on which is wound a cable 26 extending to the source of power for the two electric motors 22 and 23 which are independently operated and controlled.

Fixed rigidly to the turntable 20 and extending radially therefrom is a supporting arm 27 to which is connected a bracket 28, carrying the cutter head 29 to which is secured the elongated cutter bar 30 having an endless chain cutter guided around the periphery thereof. A driving sprocket 32 meshes with this chain and is secured by keys 31 to the lower end of a torque shaft 33 on the upper end of which is mounted a bevel gear 34. A clutch 35 is mounted on the shaft 33 for controlling operation of the sprocket 32, the clutch being operated in turn by a rock shaft 36 and lever 37. A plate 38 secured by screws 39 to the cutter head 29 serves as a guide for the chain 146 during operation of the sprocket.

As shown in Fig. 3, the armature shaft 40 which projects from the motor 22 in Fig. 1 has secured thereto a bevel pinion 41 which meshes with a horizontal bevel gear 42 secured to the vertical shaft 43. The upper end of shaft 43 is provided with a bevel gear 44 which meshes with the bevel gear 45 mounted on one end of shaft 46, the other end of the shaft carrying the bevel gear 47 which meshes with the bevel gear 34 on shaft 33, the sprocket 32 being thereby actuated responsive to operation of the clutch 35.

Before proceeding with further details of the driving mechanism for the cutter chain and the turnover head mechanism there will be described the mechanism for feeding the chain kerf-cutter on the center of the turntable, which mechanism may be understood by referring to Figs. 8 to 15 inclusive. This mechanism is substantially the same as that disclosed and claimed in my application Serial No. 656,697 filed February 14, 1933.

The ring 17 has secured to its inner edge an annular rack 98 with which meshes a pinion 99 Fig. 8 at the lower end of a vertical shaft 100, mounted in a bearing 100a on the turntable 20. Keyed to the upper end of the shaft 100 is a spur gear 101 which meshes with a spur gear 102. By means of a friction disc clutch 103 operated by the sprocket 104, the gear 102 may be connected 55 through the rotating element 105 to the vertical shaft 106. To the lower end of the shaft 106 is keyed a worm gear 107 with which meshes a worm 108 which is arranged to be operated in one direction or the other by means of the pawl and ratchet mechanism shown in Figs. 10, 11, 12 and 14.

As shown in Fig. 9 a manual wheel 109 is mounted on a shaft 110, on the opposite end of which is mounted a bevel gear 111 meshing with 65 a bevel gear 112 mounted for rotation on a vertical axis and with the sprockets 113 and 104, chain 114 connecting the two sprockets. Therefore, by rotating the wheel 109 in one direction or the other the friction clutch 103 may be applied or released to effect power transmitting connection between the worm 108 and the annular rack 98.

As shown in Fig. 11, the lower end of shaft 43 is provided with an eccentric cam 115 on the 75 periphery of which is mounted the eccentric

strap 116 to which is pivoted at 117 the reciprocating arm 118. Pivoted at 119 to the outer end of the arm 118 is a bifurcated support 120 carrying the bearing pin 121, as shown in Figs. 11 and 12.

Journalized on the pin 121 and on the shaft 108a are supporting members 122 and 123, and between these members on the pin 121 are reversely arranged pawls 124 and 125. Reversely arranged ratchets 126, 127 are keyed to the shaft 108a to 10 rotate with the latter. A pawl setting device 128 is provided with openings 128a, 128b in position to permit pawl 124 or the other pawl 125 to engage its respective ratchet wheel. A spring pressed pin 133 fits into one of the recesses 134 to hold the pawl setting device 128 in adjusted position.

By means of the lever 129, the shaft 130 may 15 be rocked in one direction or the other to operate the spur gearing 131, 132, to bring either the opening 128a or the opening 128b into position to permit one pawl 124 or the other pawl 125 to engage its ratchet wheel. A spring pressed pin 20 133 fits into one of the recesses 134 to hold the pawl setting device 128 in adjusted position.

At the right-hand end of the shaft 108a as shown in Fig. 12 is secured a brake wheel 135 with which is associated a brake band 136 which is held yieldingly applied to the brake wheel 135 by means of the springs 137, 137. During swinging feeding movement of the kerf-cutter into the mine vein, vibrations may cause partial reversal of the worm 108, while the pawl 124 or the pawl 30 125 is moving from one notch to the next notch. To overcome this tendency of the worm 108 to partially reverse its rotation, the brake mechanism shown at the right-hand end of the shaft 108a is relied on to hold the worm 108 in the position to which it had been moved by the pawl and ratchet mechanism.

To facilitate assembly or removal of the pawl and ratchet mechanism for replacement of parts, the bracket 138 for supporting the shaft 130 may 40 be removably secured by means of cap screws 139 to the turntable 20. The bracket 138 may fit into the trough 140 so as to hold in place the sections 141, 141 of the bearing for the right-hand portion of the shaft 108a.

Spaced at intervals around the peripheral portion of the turntable 20 on the underside thereof are brackets 142 in which are mounted fixed vertical bearings 143 for rollers 144 within the rings 145 which are adapted to roll around the inner 50 surface of the ring 17 as shown in Fig. 9. Lateral thrust on the turntable will therefore be taken by the roller bearings 143, 144, 145 to relieve the strain between the pinion 99 and the annular rack 98.

It will thus be seen that during swinging feeding movement, the cutter bar 30 is rigidly connected in adjusted position to the turntable 20 and the latter will be guided concentrically of the stationary ring 17 by means of the roller bearings 60 shown in Fig. 9, while the power is being transmitted very efficiently from the motor 22 to the pinion 99 to cause the same to travel along the stationary annular rack 98.

The worm gearing 107, 108, Fig. 8 is self-locking 65 and therefore when the clutch 103 is applied the cutter bar 30, Fig. 1, may be held locked in an adjusted position at an acute angle relative to the mine track. During driving of the chain cutter by means of the motor 22 and the power transmission mechanism between this motor and the chain cutter, the drum 128, Fig. 14, may be located in neutral position to hold both of the ratchet pawls 124 and 125 out of engagement with their respective ratchets.

While the cutter bar is located at an acute angle relative to the mine track, the kerf cutter may be sumped into the coal face extending across the space in advance of the mine track, 5 by traction feed which is effected by the motor 23 operating truck propelling mechanism through the reduction gearing located at 24. After the sumping cut has been completed and an arcuate feeding movement effected across the working 10 face, the traction feeding mechanism may again be operated to effect a rectilinear withdrawal movement parallel to the mine track, thereby completing the cutting of a parallel ribbed kerf. In this manner parallel ribbed kerfs may be cut 15 in relatively narrow entries or in relatively wide entries, the depth of each cut being equal to the full effective length of the cutter bar.

When arcuate feeding is effected across the working face in advance of the mine track it is 20 desirable that the cutter bits on the advance side of the cutter bar shall continuously emerge from the coal face so as to sweep the cuttings therefrom. It is also desirable to reduce the overall height of the mining machine shown in Fig. 2 25 so that it may operate in relatively low roof mine chambers or rooms, and so that it may be transported along mine entries having low roofs. By reason of the elevating screw mechanism located at 19, 19, 19a, the same machine may also be used 30 in operating in relatively high planes and by use of the turnover mechanism hereinafter described the kerf cutter may be located in relatively high planes above all other parts of the machine. When the cutter bar is inverted, however, the 35 arcuate feeding of the cutter bar should be reversed so that the cutter bits will again be on the advance side of the cutter bar. For instance, if the arcuate feed as viewed in Fig. 1, is anti-clockwise when the cutter bar is in its lower position as shown in Fig. 2, the arcuate feed should 40 be clockwise after the cutter bar has been inverted so as to occupy a top cutting position. It will thus be seen that whether the cutter bar is fed arcuately in a clockwise direction in one 45 plane or fed in an anti-clockwise direction in another plane, the cutter chain way always be kept moving in the same direction and so as to emerge from the coal face on the advance side of the cutter bar to effect sweeping of the coal cuttings 50 from the coal face. The motor 22 may be continuously operated in the same direction since the cutter chain always travels in the same direction, the reversal of arcuate feed being effected by the reverse feeding mechanism illustrated in 55 Figs. 11, 12 and 14.

It should also be noted that the elevating mechanism located at 19, 19, 19a is individually operable as shown in the patents above referred to. The 60 inclination relative to the horizontal of the kerf cutter comprising the cutter bar 30, may be adjusted since such cutter bar always remains in a plane at right angles to the axis of rotation of the turntable 20.

The details of the turnover mechanism for 65 rotarilly adjusting the plane of the cutter bar on the horizontal axis of the shaft 46 are illustrated in Figs. 3 to 7, inclusive. By referring to these views, it will be seen that the cutter head mechanism including the cutter head 29, the driving 70 sprocket 32, the clutch 35, and the shaft 33, is enclosed in a housing 48 which is provided at its rear end with a tubular extension or neck 49 supported for rotation on the bearing comprising 75 the bushing 50. At the rear end of the neck 49 apparatus is provided for rotarilly adjusting the

cutter bar from a relatively low horizontal plane to a relatively high horizontal plane, the latter plane extending above all other parts of the machine in a top cutting position.

By referring to Fig. 5 it will be seen that there 5 is keyed to the hub 47a of the beveled gear 47, a spur gear 51 which meshes with a gear 52 keyed to the front end of a shaft 53 journaled in the housing 58. At the rear end of the shaft 53 is a pinion 54 (Fig. 6) which meshes with an internal or annular gear 55a integral with the drum 55. The drum 55 as shown in Fig. 3 is journaled on the rotary neck 49 which extends rearwardly from the housing 48. A ring plate 49a fits against an annular shoulder of the neck 49 and at its periphery fits an annular recess in the peripheral portion of the drum 55 to complete the enclosure of the gears 54 and 55a. It will thus be seen that when the motor 22 drives the horizontal shaft 46, power is transmitted through the spur gears 51, 10 52 to the shaft 53 and thence to the gears 54 and 55a to effect rapid rotation of the drum 55. Consequently, whenever the motor 22 is operating the drum 55 is being rotated, so long as the neck 49 is stationary relative to the radial support 59. 15 20 25

In order to effect rotation of the neck 49 and the elongated chain kerf cutter, on the horizontal axis of the shaft 46, friction mechanism in the form of a brake is provided to produce a friction clutch between the gear 55a and the neck 30 49. The brake mechanism is illustrated in Fig. 6 and is mounted on the bracket 65' which is rigidly connected to the stationary ring 65, the latter being detachably secured by means of the bolts 67 to the flange 64 integral with the radial support 50 and extending in a plane at right angles to the shaft 46. 35

The brake mechanism illustrated in Fig. 6 comprises a pair of shoes or brake bands 56, 56, which are adjustably connected at their ends remote 40 from the bracket 65' as illustrated at 57. The brake shoes may be applied to the drum 55 by raising the lever 59 which is connected by the link 58 to the bracket 65' at 58'. It should be understood that the right hand end of the lower 45 section of the brake as viewed in Fig. 6 is rigidly secured to the bracket 65''. It will thus be seen that when the lever 59 is moved up the brake shoes 56, 56 are brought into closer contact with the drum 55 so as to apply the brake, and when 50 the lever 59 is released the spring 59' will effect automatic release of the brake mechanism.

As shown in Fig. 3 an annular groove 60 at the rear portion of the neck 49 is adapted to receive a split retaining ring 61. At the rear end of the 55 neck 49 is located an annular collar 62 which is keyed to the neck 49 by a plurality of keys as shown at 63 in Fig. 4. The collar 62 is bolted to the retaining ring 61 by means of the bolts 63a. Therefore, the collar 62 is detachably connected 60 to the rear end of the neck 49.

As above pointed out, the ring 65 is secured to the flange 64 by means of the bolts 67 as shown in Figs. 3, 5 and 6, the ring 65 being cylindrical in shape to afford a housing for the annular collar 62. An inwardly extending flange 66 on the housing 65 serves to retain the neck 49 against outward movement off the bearing 85. That is to say, since the ring 61 fits in the groove 60 of the neck 49 and the ring 61 is secured to the annular 70 collar 62 the flange 66 locks the neck 49 on the bearing 85.

In order to lock the cutter bar 30 for feeding movement in a selected plane of operation, latch mechanism is provided in connection with the pe- 75

peripheral portion of the annular collar 62. As shown in Fig. 7 two diametrically opposed notches 68, 68 are located in the periphery of the collar 62. As shown in Fig. 4 the ring 65 is provided 5 with an outwardly extending bracket 69. On this bracket is pivotally mounted a plate 70 of polygonal or other suitable configuration, which is turnable about the pivotal axis 71. By means of the handle 72 on the plate 70 the latter may be 10 moved from its full line position to its dotted line position shown in Fig. 4.

As shown in Fig. 7 the bracket 69 is provided with a guideway 73 for the spring pressed latch 76 which is adapted to fit into either of the notches 15 68, 68 to lock the collar 62 in adjusted position and therefore lock the cutter bar 30 in its selected plane of operation.

The latch 76 is operatively connected by means of the link 77 to the actuating plate 70. A pin 20 78 pivotally connects one end of the link 77 to the latch 76 and a pin 78a connects the other end of the link to the operating plate 70. Inside of the bracket 69 is a retaining seat 74 for a spring 75 which extends into a cylindrical recess in the 25 rear end of the latch 76. When the operating plate 70 is moved from its full line position to its dotted line position as shown in Fig. 4 the latch 76 is released from its notch 68 against the action of the spring 75, and when the plate 70 is 30 released the spring 75 urges the latch 76 against the peripheral surface of the collar 62 in readiness to automatically snap into the next notch 68.

It is preferred that when the latch mechanism is released and the brake applied to effect 35 rotary adjustment of the cutter head 29 on the horizontal axis of the shaft 46, the collar 62 as shown in Fig. 7 shall rotate anti-clockwise so that when the latch is released the spring 75 will act to urge the inner end of the latch 76 along the cut away portion 62', thereby permitting the 40 face 95 of the notch 68 to act as an abutment or limit stop. Therefore, as soon as the neck starts to rotate the handle 72 of the latch mechanism may be released and the brake held applied with the assurance that the limit stop 95 will definitely and accurately stop the rotation of the neck at 45 exactly the pre-selected position whereupon the latch will automatically snap into the notch 68 and prevent further rotation of the neck 49. If the brake is held applied after the latch 76 reaches the abutment 95, the drum 55 will slip relatively to the brake shoes. In other words, the brake mechanism will act in the nature of a friction clutch to permit slipping when the rotation of 50 the neck is definitely stopped at a pre-selected position.

It should be particularly noted that the turnover movement for the operation of inverting the chain kerf cutter is effected at a relatively 60 rapid rate of speed. When it is desired to effect a turnover movement of the cutter head the latch 76 is released, the brake shoes 56 applied to the drum 55 and as soon as the neck 49 starts to rotate the latch mechanism may be released. The drum 55 being connected to the shaft 46 as shown in Figs. 3, 5, and 6, the speed of rotation of the pinion 54 as it walks around the stationary annular gear 55a effects a quick turnover movement of the cutter head 29. During 65 this turnover movement the clutch 35 may be in neutral position so that the cutter chain is not being driven.

But it should be understood that the chain cutter is always driven in the same direction relative to the cutter bar and therefore it is de- 70 75

sirable to control the motor 22 to always rotate in the same direction, but this does not interfere with the desired turnover movements because it may be made through 180° in an anti-clockwise direction as viewed in Fig. 7. 5

As shown in Fig. 3 the radial support 50 is provided with cups or recesses 79, 79a for containing lubricant. The bottom of recess 79 is provided with an opening 80 which registers with an opening 82 in the bushing 81 for supplying 10 lubricant to the shaft 46. Lubricant from the recess 79a passes along the groove 83 to the bearing bushings 85, 86 and 87.

It will also be seen by referring to Fig. 3 that when the sections 90 and 91 of the clutch 35 15 are brought into engagement by actuation of either lever 31, 31 (Fig. 5), the sprocket 32 of the kerf cutter is rotated. Suitable anti-friction bearings are provided for the shaft 33. A pipe 92 may be provided for supplying lubricant to 20 the lower bearing 149. Lubricant seals 93 may be provided to prevent escape of lubricant from the bearing 149.

A ring plate 148 encircling the shaft 33 may be fitted in place on the cutter head 29 as shown 25 in Fig. 3 to prevent escape of lubricant from the bearing 149 into the chamber where the clutch 35 is located. The upper bearing 149' may be lubricated after removing the screw plug 48'. The cover 48'' may be detachably secured to the 30 housing 48 as shown in Fig. 3; by removing the cover the parts shown are rendered accessible for inspection or repairs.

In operation the chain kerf cutter may cut 35 horizontal kerfs throughout a considerable range of elevations due to the adjustments at the screw posts 19, 19, 19a, and such adjustments and elevations may be still further increased by reason of the rotary adjustment of the neck 49 on the horizontal axis of the shaft 46. The kerf 40 cutter may be adjusted not only in elevation but also in inclination because the adjustments at 19, 19, 19a may be individually effected by means of power operated mechanism. The plane of the cutter bar always remains at right angles 45 to the upright axis of swinging feeding movement of the turntable 20. By reason of the traction feed it is effected by the motor 23 and the reduction gearing 24 connected to the truck propelling mechanism the kerf cutter may make 50 long wall rectilinear feeding movements not only in the face extending across the space in advance of the mine track but also in the ribs parallel to the mine track. In making such rectilinear feeding movements the kerf cutter must 55 be in a plane parallel to the plane of the mine track but when the truck is stationary on the mine track the kerf cutter may be located in an incline plane relative to the level of the mine track because when arcuate swinging movements 60 are effected the axis is at right angles to the plane of the cutter bar. Furthermore, as above pointed out, arcuate feeding movements may be made in opposite directions with the cutter bits on the advance side or edge of the cutter bar always 65 emerging from the coal vein so as to effectively sweep the cuttings therefrom.

The shaft 33 may be extended through the cover 48'' and the drum 55 connected thereto, with the friction mechanism of Fig. 6 connected 70 between the cover 48'' and the drum, so that when the shaft 33 is held stationary and the shaft 46 is rotated, the rotation of the gear 47 will turn the head over on the axis of the shaft 46, since the gear 47 can not rotate on its own 75

axis. However, I prefer to use the construction illustrated because better control may be obtained of the turnover movement.

Obviously those skilled in the art may make 5 various changes in the details and arrangement of parts without departing from the spirit and scope of the invention as defined by the claims hereto appended, and I wish therefore not to be restricted to the precise construction herein dis- 10 closed.

Having thus described and shown an embodiment of my invention, what I desire to secure by Letters Patent of the United States is:

1. In a mining machine, the combination with 15 a wheeled truck movable on a trackway, of kerf-cutting mechanism mounted thereon and comprising a plane chain kerf-cutter, mechanism for adjusting the inclination of said kerf-cutting mechanism to the horizontal, power-operated 20 mechanism for effecting rotary adjustment of said kerf-cutting mechanism on a horizontal axis into a plurality of planes of operation, means adapted to stop said kerf-cutter in a pre-determined position of said rotary adjustment, 25 and motor-operated mechanism for operating said kerf-cutting mechanism including the feed of said kerf-cutter.

2. A mining machine comprising the combination with a truck, of a horizontally extending 30 neck, means for horizontally swinging the said neck, a cutting tool, means supported by the neck and supporting the cutting tool on the neck, a neck shaft in the neck, means operatively connecting the neck shaft and the cutting tool for 35 cutting, and mechanism operable by the neck shaft for effecting adjustment of the cutting tool into a plurality of different planes, the said mechanism including a shaft extending parallel to the neck shaft, operating mechanism at one 40 end of the shaft and interconnecting the said shaft with the neck shaft, a pinion on the other end of the said shaft, a drum, an annular gear within the drum and meshing with the said pinion, the gear and drum normally revolving around 45 the pinion, and brake mechanism for securing the drum and gear against rotation, whereby the pinion runs around the gear to effect an arcuate adjustment of the cutting tool.

3. In a mining machine, the combination with 50 a portable base, of an elongated chain kerf-cutter comprising an elongated cutter bar, a support for said kerf-cutter rotatably mounted on said base, a shaft extending along the axis of said rotatable support, power-transmission mechanism between said shaft and said kerf-cutter to drive the same, friction mechanism for effecting adjustment of the kerf-cutter into a plurality of different planes by transmitting a turning movement from said shaft to said rotatable support 55 and automatic means for positioning said kerf-cutter at a predetermined plane of adjustment.

4. In a mining machine, the combination with 60 cutter supporting and directing means movable on a trackway into operative position at right angles to a face, of cutter mechanism supported thereon comprising a cutter chain-carrying cutter bar adapted to cut a path for itself when presented edgewise to the face, power mechanism operable responsively to operation of the cutter 65 mechanism for effecting a rotary adjustment of the cutter bar into predetermined planes, and spring-pressed lock mechanism adapted to stop the cutter mechanism in a predetermined position and to hold the cutter mechanism in said 70 predetermined position.

5. A mining machine comprising the combination with a wheeled truck movable on a trackway, of a turntable on the truck, cutter mechanism supported by the turntable and comprising a cutter head and a cutter bar, power transmission mechanism for operating the cutter mechanism, and mechanism driven by the said power transmission mechanism for effecting rotary adjustments of the cutter bar, the said mechanism including a shaft, a drive pinion on the shaft, a 10 drum, an internal gear in the drum meshing with the drive pinion for normally rotating the drum, and brake means on the drum for braking the drum to enable the pinion to run around the said ring gear to effect turn-over movements of the 15 cutter mechanism.

6. A mining machine comprising the combination with supporting means movable on a trackway, of cutter mechanism thereon comprising a cutter bar having a chain adapted to cut a 20 kerf in a face when the said bar is presented thereto, mechanism supported by the truck for moving the bar either angularly across the end of the truck or longitudinally relative to the trackway at a feeding speed to cut either a right 25 angle or a parallel face, mechanism for effecting a rotary adjustment of the bar on a horizontal axis to cut a kerf in the face in a plurality of different planes, and means for stopping and securing the mechanism in a predetermined ad- 30 justed position, the said means including a latch, spring means normally urging the latch into latching engagement with the said mechanism, and means for withdrawing the latch from the 35 said latching engagement.

7. A mining machine comprising the combination with a wheel truck adapted to travel on a mine track, of a turntable mounted on the truck for adjustment relatively thereto, kerf-cutting mechanism, a support for the said mechanism including power transmission mechanism therefor, a housing for the kerf-cutting mechanism rotatably mounted on the support, and means operated by the power transmission mechanism for effecting a rotary adjustment of the kerf- 40 cutting mechanism, the mechanism including a normally rotating drum, and brake mechanism 45 on the drum for holding the drum stationary for enabling the said means to turn over the cutting 50 mechanism.

8. A mining machine comprising the combination with cutter supporting and directing means movable on a trackway into operative position relative to a face, of cutter mechanism supported thereon, and adjusting mechanism for effecting turn-over movement of the cutter mechanism, the said adjusting mechanism including a drum, means for rotating the drum relatively to the cutter mechanism, and releasable friction mechanism for holding the drum stationary while 55 enabling the rotating means to continue operating, thereby effecting turn-over movement of the cutting mechanism.

9. A mining machine comprising the combination with cutter supporting and directing means movable on a trackway into operative position relative to a mine face, of cutter mechanism supported thereon, and turn-over mechanism for the cutter mechanism, the said turn-over mechanism including a drum, means for rotating the drum relatively to the cutter mechanism, and releasable brake mechanism on the exterior of the drum adapted to grip the drum to hold it 60 stationary. 70 75

10. A mining machine comprising the combination with cutter supporting and directing means movable on a trackway into operative position relative to a mine face, of cutter mechanism supported thereon, adjusting mechanism for the cutter mechanism, and means for locking the cutter mechanism in adjusted position, the said means including a collar associated with the cutter mechanism and rotatable therewith and provided with latching recesses, the said collar having its peripheral surface eccentrically formed adjacent one side of each of the notches, thereby providing an abutment at the opposite side of each notch for engagement by a latch to guide 10 the latch into the notch and to prevent overturning of the cutter mechanism, a latch member adapted to fit into the said notches, and releasable means for pressing the latch into engagement with the periphery of the said collar 15 and for causing the latch to snap into engagement with the said notches upon either notch and its adjacent abutment becoming presented to the latch.

11. In a mining machine, the combination with 25 a body, of a kerf-cutting mechanism pivotally mounted thereon for pivotal movement about a substantially horizontal axis, power-operated mechanism for rotating said kerf-cutting mechanism on said axis, means adapted to stop rotation of said kerf-cutting mechanism at a predetermined position, and motor operated mechanism for operating said kerf-cutting mechanism to effect a cutting operation.

12. In a mining machine, the combination with 35 a body, of a kerf-cutting mechanism pivotally mounted thereon for pivotal movement about a substantially horizontal axis, power-operated mechanism for rotating said kerf-cutting mechanism on said axis, means adapted to stop rotation of said kerf-cutting mechanism at any one 40 of a plurality of desired predetermined positions, and motor operated mechanism for operating said kerf-cutting mechanism to effect a cutting operation.

45. 13. A mining machine comprising the combination with a body, of a kerf-cutting mechanism having a head pivotally mounted on said body for pivotal movement about a substantially horizontal axis, a motor, a shaft adapted to be driven by said motor for driving said kerf-cutting mechanism, said shaft having an axis common with said first mentioned axis and extending from said body into said head, a second shaft carried by said head and having an axis parallel 55 to and spaced from the axis of said shaft, gears connecting said shafts, a pinion on said second shaft, a drum having an internal ring gear in mesh with said pinion, said drum being normally free to rotate under the influence of said second shaft, and means to restrict rotation of said drum while said second shaft is rotated whereby 60 said head will rotate with respect to said body.

14. A mining machine comprising the combination with a body, of a kerf-cutting mechanism having a head pivotally mounted on said body for pivotal movement about a substantially horizontal axis, a motor, a shaft adapted to be driven by said motor for driving said kerf-cutting mechanism, said shaft having an axis common with 65 said first mentioned axis and extending from said body into said head, a second shaft carried by said head and having an axis parallel to and spaced from the axis of said shaft, gears connecting said shafts, a pinion on said second shaft, a drum having an internal ring gear in 70

mesh with said pinion, said drum being normally free to rotate under the influence of said second shaft, and means to restrict rotation of said drum while said second shaft is rotated whereby said head will rotate with respect to said body, 5 said means comprising a brake mechanism.

15. A mining machine comprising the combination with a body, of a kerf-cutting mechanism having a head pivotally mounted on said body for pivotal movement about a substantially horizontal axis, a motor, a shaft adapted to be driven by said motor for driving said kerf-cutting mechanism, said shaft having an axis common with said first mentioned axis and extending from said body into said head, a second shaft carried by said head and having an axis parallel to and spaced from the axis of said shaft, gears connecting said shafts, a pinion on said second shaft, a drum having an internal ring gear in mesh with said pinion, said drum being normally 20 free to rotate under the influence of said second shaft, and means to restrict rotation of said drum while said second shaft is rotated whereby said head will rotate with respect to said body, 25 said means comprising a brake mechanism attached to said body.

16. In a mining machine, the combination with a body, of a kerf-cutting mechanism including a plane cutter-bar and a cutter-chain, a cutter-bar head pivotally connecting said cutter-bar to said 30 body for pivotal movement about an axis substantially parallel with the plane of said cutter-bar, a motor driven shaft extending from said body along said axis and into said head for driving said cutter-chain, a second shaft, said 35 second shaft being carried in said head on an axis parallel with and spaced from the axis of said motor driven shaft, said shafts being interconnected, a pinion gear carried by said second shaft, and stationary means attached to said body 40 for effecting a driving connection between said gear and said body whereby rotation of said second shaft will produce rotation of said head about its pivotal axis, said stationary means comprising a brake and means for operating said 45 brake.

17. In a mining machine, the combination with a body, of a kerf-cutting mechanism including a plane cutter-bar and a cutter-chain, a cutter-bar head pivotally connecting said cutter-bar to 50 said body for pivotal movement about an axis substantially parallel with the plane of said cutter-bar, a motor driven shaft extending from said body along said axis and into said head for driving said cutter-chain, a second shaft, said 55 second shaft being carried in said head on an axis parallel with and spaced from the axis of said motor driven shaft, said shafts being interconnected, a pinion gear carried by said second shaft, a drum loosely journaled to said body for rotation about the axis of said motor driven shaft, said drum having an internal gear in mesh with said pinion gear, and stationary brake means for restricting the free rotation of said drum whereby rotation of said second shaft will produce rotation 60 of said head about its pivotal axis.

18. In a mining machine, the combination with a body, of a kerf-cutting mechanism including a plane cutter-bar and a cutter-chain, a cutter-bar head pivotally connecting said cutter-bar to 70 said body for pivotal movement about an axis substantially parallel with the plane of said cutter-bar, a motor driven shaft extending from said body along said axis and into said head for driving said cutter-chain, a second shaft, said 75

shaft being carried in said head on an axis parallel with and spaced from the axis of said motor driven shaft, said shafts being interconnected, a pinion gear carried by said second 5 shaft, a drum loosely journaled to said body for rotation about the axis of said motor driven shaft, said drum having an internal gear in mesh with said pinion gear, and brake means carried by said body for restricting the free rotation of said drum 10 whereby rotation of said second shaft will produce rotation of said head about its pivotal axis.

19. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor driven shaft extending from said body along said axis and into said head for 15 driving said cutter-chain, a second shaft, said second shaft being carried in said head on an axis parallel with and spaced from the axis of said motor driven shaft, said shafts being interconnected, a pinion gear carried by said second shaft, 20 stationary means attached to said body for effecting a driving connection between said gear and said body whereby rotation of said second shaft will produce rotation of said head about its pivotal axis, and means adapted to stop rotation 25 of said head in predetermined positions.

20. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor driven shaft extending from said body along said axis and into said head for 30 driving said cutter-chain, a second shaft, said second shaft being carried in said head on an axis parallel with and spaced from the axis of said motor driven shaft, said shafts being interconnected, a pinion gear carried by said second shaft, 35 stationary means attached to said body for effecting a driving connection between said gear and said body whereby rotation of said second shaft will produce rotation of said head about its pivotal axis, and means adapted to stop rotation 40 of said head in predetermined positions, said second shaft being carried in said head on an axis parallel with and spaced from the axis of said motor driven shaft, said shafts being interconnected, a pinion gear carried by said second shaft, 45 stationary means attached to said body for effecting a driving connection between said gear and said body whereby rotation of said second shaft will produce rotation of said head about its pivotal axis, and means adapted to stop rotation 50 of said head in predetermined positions, said last named means comprising a notched ring attached to said head for rotation therewith, a spring-pressed latch carried by said body and adapted to ride on said ring and snap into a notch 55 therein when said latch is opposite said notch.

21. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor driven shaft extending from said body along said axis and into said head for driving 60 said cutter-chain, a second shaft, said second shaft being carried in said head on an axis parallel with and spaced from the axis of said motor driven shaft, said shafts being interconnected, a pinion gear carried by said second shaft, 65 stationary means attached to said body for effecting a driving connection between said gear and said body whereby rotation of said second shaft will produce rotation of said head about its pivotal axis, and means adapted to stop rotation of said head in predetermined positions, said last named 70 means comprising a ring attached to said head for

rotation therewith and having abutments, a spring-pressed latch carried by said body and adapted to ride on said ring and to strike said abutments.

22. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor driven shaft extending from said body along said axis and into said head for driving said cutter-chain, a second shaft, said second shaft being carried in said head on an axis parallel with and spaced from the axis of said motor driven shaft, said shafts being interconnected, a pinion gear carried by said second shaft, stationary means attached to said body for effecting a driving connection between said gear and said body whereby rotation of said second shaft will produce rotation of said head about its pivotal axis, means adapted to stop rotation of said head in predetermined positions, said last named means comprising a notched ring attached to said head for rotation therewith, a spring-pressed latch carried by said body and adapted to ride on said ring and snap into a notch therein when said latch is opposite said notch, and means for rendering said stop means inoperative.

23. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor driven shaft extending from said body along said axis and into said head for driving said cutter-chain, a second shaft, said second shaft being carried in said head on an axis parallel with and spaced from the axis of said motor driven shaft, said shafts being interconnected, a pinion gear carried by said second shaft, 35 stationary means attached to said body for effecting a driving connection between said gear and said body whereby rotation of said second shaft will produce rotation of said head about its pivotal axis, means adapted to stop rotation of said head in predetermined positions, said last named means comprising a ring attached to said head for rotation therewith and having abutments, a spring-pressed latch carried by said body and adapted to ride on said ring and to strike said abutments, and means for rendering said stop means inoperative.

24. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor, driving connections between said motor and said cutter-chain for driving said cutter-chain, means for rotating said head about its axis, and means operating automatically to stop rotation of said head in a predetermined position.

25. In a mining machine, the combination with a body, of a kerf-cutting mechanism including a plane cutter-bar and a cutter-chain, a cutter-bar head pivotally connecting said cutter-bar to said body for pivotal movement about an axis substantially parallel with the plane of said cutter-bar, a motor, driving connections between said motor and said cutter-chain for driving said cutter-chain, means for rotating said head about 70 its axis, and means for rendering said stop means inoperative.

its axis comprising means for effecting an impositive connection between said motor and said head, and means operating automatically to stop rotation of said head in a predetermined position.

5 26. In a mining machine, the combination with a body, of a kerf-cutting mechanism including a plane cutter-bar and a cutter-chain, a cutter-bar head pivotally connecting said cutter-bar and said body for pivotal movement about an axis 10 substantially parallel with the plane of said cutter-bar, a motor, driving connections between said motor and said cutter-chain for driving said cutter-chain, means for rotating said head about its axis comprising means for effecting an im- 15 positive connection between said motor and said head, and means operating automatically to stop rotation of said head in a predetermined position, said stop means comprising a notched ring attached to said head for rotation therewith, a 20 spring-pressed latch carried by said body and adapted to ride on said ring and snap into a notch therein when said latch is opposite said notch.

27. In a mining machine, the combination with a body, of a kerf-cutting mechanism including a plane cutter-bar and a cutter-chain, a cutter-bar head pivotally connecting said cutter-bar and said body for pivotal movement about an axis 25 substantially parallel with the plane of said cutter-bar, a motor, driving connections between said 30 motor and said cutter-chain for driving said cutter-chain, means for rotating said head about its axis comprising means for effecting an impositive connection between said motor and said head, and means operating automatically to stop rotation of said head in a predetermined position, said 35 stop means comprising a ring attached to said head for rotation therewith and having abutments, a spring-pressed latch carried by said body and adapted to ride on said ring and to strike said 40 abutments.

28. In a mining machine, the combination with a body, of a kerf-cutting mechanism including a plane cutter-bar and a cutter-chain, a cutter-bar head pivotally connecting said cutter-bar and said body for pivotal movement about an axis 45 substantially parallel with the plane of said cutter-bar, a motor, driving connections between said motor and said cutter-chain for driving said cutter-chain, means for rotating said head about its 50 axis comprising means for effecting an impositive connection between said motor and said head, and means operating automatically to stop rotation of said head in a predetermined position, said stop means comprising a notched ring at- 55 tached to said head for rotation therewith, a spring-pressed latch carried by said body and adapted to ride on said ring and snap into a notch therein when said latch is opposite said notch, and means for rendering said stop means inop- 60 erative.

29. In a mining machine, the combination with a body, of a kerf-cutting mechanism including a plane cutter-bar and a cutter-chain, a cutter-bar head pivotally connecting said cutter-bar and said body for pivotal movement about an axis 5 substantially parallel with the plane of said cutter-bar, a motor, driving connections between said motor and said cutter-chain for driving said cutter-chain, means for rotating said head about its axis comprising means for effecting an impositive connection between said motor and said head, and means operating automatically to stop rotation of said head in a predetermined position, said stop means comprising a ring attached to said head for rotation therewith and having 10 abutments, a spring-pressed latch carried by said body and adapted to ride on said ring and to strike said abutments, and means for rendering said stop means inoperative.

30. In a mining machine, a frame, a motor 20 thereon, a cutter head disposed forwardly of said motor, said cutter head including a support member, a frame member disposed forwardly thereof and carried thereby for pivotal movement about an axis extending longitudinally of said frame, a 25 projecting cutter bar carried by said frame member having a cutter chain movable thereabout, means for driving said cutter chain about said cutter bar comprising a shaft, a drive connection from said motor to said shaft, and a drive 30 connection from said shaft for rotatably moving said frame member about an axis extending longitudinally of said support member including a gear mounted in said support member for rotatable movement with respect thereto, a geared connection from said shaft to said gear and yieldable means operably connectible with said support member for selectively locking said gear from movement with respect to said support member and permitting said gear to move with respect 40 thereto upon overload thereof.

31. A mining machine comprising the combination with supporting means movable on a trackway, of cutter mechanism thereon comprising a cutter bar having a chain adapted to cut a kerf in a face when the said bar is presented thereto, means for moving the said bar transversely of the trackway, and mechanism for effecting a rotary adjustment of the bar to cut a second kerf in the face parallel to the first-mentioned kerf, the said mechanism comprising a ring gear intermeshing with a pinion, the pinion being positioned interiorly of the gear and being adapted to drive the gear during kerf-cutting operations, and means for securing the gear against rotation, thereby causing the pinion to ride around the gear for effecting a turning-over of the position of the cutter bar.
